R. J. HODGE

SLIDE BUCKLE

Filed April 28, 1927

Inventor.
Robert J. Hodge
Seymour Earle Nichols
Atty

UNITED STATES PATENT OFFICE.

ROBERT J. HODGE, OF WEST HAVEN, CONNECTICUT, ASSIGNOR TO THE AMERICAN BUCKLE CO., OF WEST HAVEN, CONNECTICUT, A CORPORATION.

SLIDE BUCKLE.

Application filed April 28, 1927. Serial No. 187,286.

My invention relates to an improvement in slide-buckles primarily designed to be used on the shoulder-straps of overalls, a slide-buckle of this type being shown in United 5 States Patent No. 1,431,661, granted October 10, 1922, on an application filed by me. The object of my present invention is to produce a superior buckle of the type shown in the patent referred to.

10 In the accompanying drawings:

Fig. 1 is a view in front elevation showing my improved buckle applied to the shoulder-strap of an overall;

15 Fig. 2 is a view thereof in vertical longitudinal section on the line 2—2 of Fig. 1;

Fig. 3 is a corresponding view showing a different mode of applying the web and showing the rocking of the slide-bar of the frame, due to placing the strap under draft;

20 Fig. 4 is a detached view of the buckle in elevation;

Fig. 5 is an enlarged view thereof in transverse section on the line 5—5 of Fig. 4; and

25 Fig. 6 is a view of the buckle in longitudinal section on the line 6—6 of Fig. 5.

In carrying out my invention, I produce, preferably from a single length of wire, a substantially-rectangular buckle-frame having two parallel end-bars 10 and two parallel 30 side-bars 11, the latter being symmetrically flattened in the plane of the frame on opposite sides of their centers to form strap-grips 12, the inner edges of which project inward into the frame. Upon the end-bars 10 of the 35 frame I mount a wire slide-bar 13 struck up so as to form oppositely-extending projections or teeth 14 substantially located in the plane of the frame or projections being arranged, as shown, in pairs. Such specific ar-

40 rangement is not essential, though it is essential that the teeth shall be formed so as to lie substantially in the plane of the frame, whereby they are prevented from penetrating and chafing or tearing the shirt or other garment 45 of the wearer. As shown, the slide-bar 13 is longitudinally bent or undulated to form a central high-point 15 and two lateral high-points 16, the latter substantially registering with the central portions of the flattened 50 strap-grips 12 of the buckle-frame. At its ends the bar is formed with eyes 17 embracing the end-bars 10 of the frame and enough larger in internal diameter than the diameter thereof to permit the bar to slide upon the

said end-bars, as well as to rock thereupon 55 when the strap 18 is threaded through the buckle and placed under tension, the strap being provided in the usual manner with a button-loop 19.

When the strap is threaded through the 60 buckle in the usual manner, it is deflected thereby, as shown in Figs. 2 and 3, and a bight secured upon it, this bight being heightened by the inwardly-projecting portions of the strap-grips 12, as well as by the projections 14 of the side-bar in the plane of the buckle. By providing both of the side-bars 65 of the frame with flattened strap-grips, the buckle may be applied to the slide with either of the parallel side-bars of its frame uppermost, which is a matter of considerable convenience in applying the buckles to the shoulder-straps of overalls.

70 The flattened strap-grips 12 provide surfaces large enough for being stamped, if desired, with names or other descriptive material, or with ornamental designs.

I claim:

1. A slide-buckle, comprising a substantial- 80 ly-rectangular wire-frame having two parallel side-bars and two parallel end-bars, the said side-bars being symmetrically-flattened on opposite sides of their centers to form strap-grips projecting into the frame in the plane thereof; and a wire slide-bar slidably 85 mounted upon the said end-bars of the frame and bent to form a central high-point and two lateral high-points, the latter substantially registering with the central portions of the said strap-grips of the side-bars and provided with oppositely-projecting integral 90 teeth located in the plane of the frame to coact with the said strap-grips.

2. A slide-buckle, comprising a substantially-rectangular wire frame having two 95 parallel side-bars and two parallel end-bars, both of the said side-bars being symmetrical- ly-flattened on opposite sides of their centers to form strap-grips projecting into the frame in the plane thereof; and a slide-bar slidably 100 mounted upon the end-bars of the frame and bent to form two lateral high-points substantially registering with the central portions of the said strap-grips.

3. A slide-buckle, comprising a substantial- 105 ly rectangular one-piece wire-frame having two parallel side-bars and two parallel end-bars, both of the side-bars being symmetri-

cally flattened on opposite sides of their centers to form strap-grips projecting into the frame in the plane thereof, and a slide-bar slidably mounted on the end-bars of the frame and bent on opposite sides of its center to form high-points substantially registering with the central portions of the said strap-

grips, and teeth formed by swaging the said slide-bar so as to project therefrom for co-action with the said strap-grips. 10

In testimony whereof, I have signed this specification.

ROBERT J. HODGE.
